UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

ORNAMENTAL-STITCH SEWING-MACHINE.

1,283,477.

Specification of Letters Patent.

Patented Nov. 5, 1918.

Application filed February 8, 1917. Serial No. 147,295.

To all whom it may concern:

Be it known that I, ALBERT H. DE VOE, a citizen of the United States, residing at Westfield, in the county of Union and State 5 of New Jersey, have invented certain new and useful Improvements in Ornamental-Stitch Sewing-Machines, of which the following is a specification, reference being had therein to the accompanying drawings.

- 10 This invention relates to improvements in ornamental stitch sewing machines and especially to machines having stitch-forming mechanism comprising one or more needles and supplemental loop-taking means, and 15 thread-handling mechanism for the ornamental thread including one or more thread-looping implements or loopers mounted for universal movement transversely of the needle or needles and adapted to present a 20 thread or threads to the needle or needles in the formation of various ornamental seams differing in configuration.

The present construction is an improvement of the machine disclosed in my copending application Serial No. 119,211, filed 25 September 9, 1916, in which the loopers for the ornamental threads are sustained by the presser-bar for universal movement transversely of the needles and are actuated 30 through connections with a pair of angularly displaced rotating cranks carried by a cross-shaft geared to rotate at half the speed of the main-shaft. In my prior construction the looper-actuating mechanism includes 35 freely fitting pin-and-socket connections permitting the presser-bar to be lifted for insertion and removal of work.

One of the objects of the present invention is to simplify the looper-actuating mechanism of my prior construction and avoid the 40 use of the pin-and-socket connections, while permitting rising and falling movements of the presser-bar.

Another object of the invention is to improve the timing of the loopers, whereby 45 they are given a substantial dwell in their advanced positions during the first part of the down-stroke of the needles.

The above and other objects, to be herein- 50 referred to, are attained by the present construction which is embodied in a sewing machine having a main-shaft disposed below the cloth-plate and connected by a pitman to a needle-actuating rock-shaft journaled 55 in the bracket-arm of the machine. The

needle-bar carries a plurality of needles which coöperate with suitable loop-taking means, such as non-thread-carrying loopers, disposed below the cloth-plate and actuated in a well known manner. The machine also 60 includes suitable feeding mechanism for advancing the work to and beyond the stitching point.

In the present construction the loopers for the ornamental threads are formed with 65 thread-delivering tubes and are sustained for universal movement transversely of the needles by a looper-supporting frame secured to the presser-bar at a point below the machine head. The rearwardly disposed 70 looper is supported in rear of the presser-foot and projects forwardly toward stitching position under the arched or bifurcated shank of the latter. The forwardly disposed looper is supported by a lever pivotally 75 sustained in front of the stitching point.

The loopers are simultaneously projected toward and retracted from the needles by a train of connections actuated through a toggle-link connection with a crank-pin carried 80 by the needle-actuating rock-shaft. During the first part of the downstroke of the needles no substantial movement is imparted to the looper-tubes, the tip ends of which are at this time projected across a line joining 85 the needles. The loopers are vibrated in unison transversely of the line of feed through mutually independent connections with a bell-crank-lever pivoted at the rear side of the bracket-arm and rocked by a link- 90 connection with a crank-pin on a counter-shaft journaled below the cloth-plate. The counter-shaft is geared to the main-shaft to rotate at half the speed of the latter in order 95 that the loopers may be vibrated transversely of the line of feed at half the frequency of reciprocation of the needle-bar.

In the accompanying drawings forming a part of this specification, Figure 1 is a front elevation of the machine with the cloth-plate 100 and certain of the working parts indicated by dotted lines. Fig. 2 is a rear elevation of the machine. Fig. 3 is a plan view. Fig. 4 is a front end elevation. Fig. 5 is a horizontal section through the presser-bar, at a 105 point just below the machine head showing the looper mechanism for the ornamental threads in plan. Fig. 6 is an elevation of the looper mechanism for the ornamental threads from the side opposite that shown in 110

Fig. 4. Fig. 7 is a perspective view of the looper-supporting frame. Figs. 8 and 9 are perspective views of the ornamental thread loopers. Figs. 10, 11 and 12 are detailed views of the presser-foot construction. Figs. 13, 14, 15 and 16 are plan views illustrating the four successive positions assumed by the looper-thread tubes relatively to the needles during a complete cycle of movement. Fig. 17 is a plan view on an enlarged scale of the seam illustrated in Figs. 13 to 16 inclusive.

In the preferred embodiment of the invention, as illustrated, the machine frame comprises the usual base 1, raised cloth-plate 2, standard 3 and bracket-arm 4 terminating in the head 5. The main-shaft 6, journaled lengthwise of the base 1 and disposed below the cloth-plate 2, is formed with the usual crank 7 which is connected by the pitman 8 to the rocker-arm 9 fixed to the needle-actuating rock-shaft 10 journaled within and lengthwise of the bracket-arm 4. Secured to the needle actuating rock-shaft 10, within the head 5, is a rocker 11 whose forward arm 11^a, Fig. 4, is connected through the usual pitman 12 to the needle-bar 13 which is journaled to reciprocate in suitable bearing sleeves 14, 14, sustained by the head 5. The needle-bar terminates in a needle-clamp 15 carrying one or more needles. In the present instance the needle-clamp is socketed to receive four needles n' , n^2 , n^3 and n^4 which are disposed in a row extending across the line of seam-formation.

Any suitable form of loop-taker mechanism may be provided to coöperate with the needles in the production of stitches. In the present embodiment I have shown four non-thread-carrying loopers 16 which are sustained by a looper-carrier 17 journaled to rock and slide upon a fixed shaft 18. An eccentric carried by the main-shaft 6 acts to impart loop-seizing and sidewise movements to the loopers in a well-known manner through the eccentric-strap 19 formed with a sleeve 20 embracing the inclined pin 21 fixed to the looper-carrier 17.

Journalized in the head 5, behind the needle-bar 13 is the presser-bar 22 which is urged downwardly by the leaf-spring 23 and may be lifted by the usual hand-operated cam-lever 24 which acts upon the roller 25 sustained by the pin 26 projecting from the block 27 apertured to fit on the presser-bar 28 and secured to the latter by a set-screw 28. To prevent turning movements of the presser-bar the block 27 is provided with a laterally projecting pin 29, Fig. 2, which is slidably received within the aperture 30 formed in the block 31 fixed to the upper end of the slide-bar 32 which is journaled in the head 5 in parallelism with the needle-bar.

Fixed to the lower end of the presser-bar 22 is the arched or bifurcated presser-foot

supporting frame 33, Figs. 10, 11 and 12, whose downwardly projecting bifurcations are slotted at 34 to slidably receive the shanks 35 of the yielding sole-pieces 36 and the connected shank portions 37, 37 of the chaining foot 38 which is disposed between the sole-pieces 36 closes the rearward side of the needle aperture 39 defined by said sole-pieces. Each of the sole-pieces 36 is formed with a rib 40 which is fitted within an undercut slot in its respective supporting shank 35 and is pivoted to the latter at 41. Rigidly secured to the shank-portions 35, respectively, are vertical slide-pins 42, each of which is fitted within a suitable aperture in the presser-foot supporting frame 33 and at its upper end carries a screw 43, which serves to limit the downward movement of the pin 42 under the action of a spring 44 which bears downwardly on the shank 35. Rigidly secured to the shank-portions 37 of the chaining foot 38 are vertical slide-pins 45, 45, each of which is fitted within a corresponding aperture in the frame 33 and at its upper end carries a screw 46 which serves to limit its downward movement under the action of the surrounding spring 47. Co-operating with the presser-foot to feed the work is the plural-sectioned feed-dog f which is supported and actuated by any suitable mechanism such, for example, as that disclosed in my Patent No. 14,218, reissued November 28, 1916.

The loopers which present the ornamental threads to the needles are supported by a looper-frame 50 apertured to receive the presser-bar 22 and fixed to the latter below the machine-head 5 by a set-screw 51. The frame 50 is slotted at 52 to embrace the reduced lower extremity of the slide-bar 32 which thus serves to prevent accidental turning of said frame on the presser-bar. Journalized in the horizontal bearing aperture 53 in the frame 50 is a rock-shaft 54 to one end of which is clamped the split socketed extremity 55, Fig. 4, of an arm 56 in whose opposite sleeved extremity 57 is journaled the upwardly extending looper-carrying shaft 58 to the lower end of which is fixedly secured the rearwardly disposed looper 59 which extends forwardly under the arched presser-foot frame 33 and terminates in the thread-tubes 60. The looper-frame 50 is formed with a slotted lug 61 to guide the rock-arm 56. A collar 62, secured to the looper-shaft 58 above the sleeved extremity 57 of the rock-arm 56, serves to support the shank of the looper 59 snugly against the lower end of the sleeve 57. From the above description it will be seen that looper-tubes 60 may move toward and from the plane of the needles by rocking about the axis of the shaft 54 and may move laterally of the line of seam formation by rocking about the axis of the looper-shaft 58. Loosely mounted on the

looper-shaft 58, Figs. 3 and 4, between the spaced collars 63, 63 is a sleeve 64 formed with a lateral lug 65 apertured to receive a cross-pin 66, whose oppositely projecting ends are journaled in one forked extremity of a pitman 67 whose opposite and offset forked extremity embraces and is pivotally connected at 68 to a rearward extension 11^b of the double rock-arm 11. When the needles 10 are at the end of their up-stroke, the center 68 is slightly below a line connecting the centers 10 and 66. Hence, during the first part of the down-stroke of the needles, the looper-tubes 60 are caused to dwell in their 15 longitudinal component of motion.

The looper-tubes 60 are given their lateral component of motion by means of the following mechanism: Fixed to the shaft 6, Fig. 1, is a pinion 70 which meshes with a spur gear 71 of double its size fixed to a counter-shaft 72 journaled in bearings 73, 73, Fig. 2, formed in the bracket 74 screwed to the bed 1 at 75. The shaft 72 is formed with a crank-arm 76 carrying the ball-ended crank-pin 77 which is embraced by the lower strapped end of a pitman 78 whose upper strapped end embraces a similar pin 79 fixed to the rear end of one arm 80 of a bell-crank lever fulcrumed at 81 to the rear side of the 20 bracket-arm 4. The other arm 82 of the bell-crank-lever carries oppositely projecting ball-ended pins 83, 84, of which the pin 83 is embraced by one strapped end of the link 85 whose opposite strapped end embraces a 25 similar pin 86 formed at one end of a crank-arm 87 whose opposite split-socketed end 88 is clamped to the looper rock-shaft 58 at a point just below the lowermost collar 63. By virtue of the two-to-one speed-reduction effected by the gears 70, 71, the looper-tubes 30 60 are vibrated laterally at half the frequency of reciprocation of the needles. The timing is such that the crank-pin 77 crosses the dead-center positions, relatively to the 35 pitman 78 and shaft 72, during the first part of the down-stroke of the needles, thus causing the looper-tubes 60 to dwell at each extremity of their lateral component of motion.

40 Journaled in a horizontal bearing aperture 90, Fig. 7, in the angular extension 91 of the looper supporting frame 50 is a headed pin 92, Fig. 5, to whose extremity 93 is clamped the split fulcrum-boss 94 of a supporting lever comprising a forwardly disposed angular lever-arm 95 and a rearwardly extending power-arm 96. The lever-arm 95 terminates in a horizontally apertured boss 97 in which is fulcrumed the 45 screw-pin 98 sustained by the looper-lever 99 to whose downwardly extending arm 100 is secured the forwardly disposed looper 101 which is formed at its extremity with a thread-tube 102. The power-arm 96 of the 50 supporting lever 95, 96, Fig. 6, is pivotally 55

connected at 103 to one end of a short link 104 whose opposite end is pivotally connected at 105 to the forward end of a crank-arm 106 whose opposite split-socketed end is clamped to the rock-shaft 54 which derives 70 its movements from the rock-arm 56. As thus connected, the thread-tubes 60 and 102 are caused to simultaneously approach and recede from the plane of the needles.

To cause the thread-tube 102 to partake of 75 the lateral motion of the thread-tubes 60, the looper-lever 99 is provided at its upper end with a ball-ended pin 107, Fig. 1, which is connected by a link 108 to a similar pin 109 carried by a slotted plate 110 adjustably secured to the rock-arm 111 by means of a screw 112 passing through a slot in said plate. The rock-arm 111 is fixed to one end of a cross-shaft 113 journaled in a bearing bracket 114 secured to the upper side of the 80 bracket-arm 4 by a screw 115. Rigidly connected to the opposite end of the cross-shaft 113, Fig. 2, is a crank-arm 116 formed at its lower end with guide-flanges 117 defining a seat within which is adjustably secured the 85 slotted shank of an arm 118 which forms an extension of the crank-arm 116 and carries a ball-ended pin 119 which is connected by the link 120 to the ball-ended pin 84 previously referred to. By means of the toggle-link 90 connection 67 with the needle-actuating rock-shaft 10, the looper-tubes 60 and 102 are caused to simultaneously approach and recede from the plane of the needles while, at the same time, the looper-tubes are caused 100 to vibrate in unison laterally of the line of seam-formation by means of the connection through the gears 70, 71 with the main-shaft 6.

The manner in which the loopers 59 and 105 101 coöperate with the needles to form an ornamental seam will be understood from an inspection of Figs. 13 to 16, inclusive. Fig. 13 illustrates the operative relation of the thread-tubes 60, 102, 60 and the needles n' , n^2 , n^3 and n^4 , at the period of the stitch-forming cycle at which the needle-points are just entering the fabric, the needles n' , n^2 and n^3 having passed down close beside the thread-tubes 60, 102, 60, respectively. Fig. 110 14 illustrates the position of the parts as the rising needles are leaving the fabric; the thread-tubes having been retracted from the plane of the needles and moved slightly to the right. The work is now fed a stitch-length during which time the thread-tubes are moved still farther to the right and projected toward the plane of the needles, passing under the then raised needle-points to the position shown in Fig. 15 wherein the 115 needle-points are again entering the fabric. In this position the thread-tubes 60, 60, are laying their respective threads, previously caught by the needles n' , n^3 , about the needles n^2 , n^4 , while the thread-tube 102 lays 120 125 130

its thread about the needle n^3 . Fig. 16 shows the position of the parts as the needles are subsequently leaving the fabric. During the next feeding stroke the thread-tubes are moved toward the position shown in Fig. 13 for a repetition of the cycle of operations.

The seam illustrated in Fig. 17 is formed when a four-needle machine is equipped with a rearwardly disposed double-tube looper, 10 and a forwardly disposed single-tube looper, as in the embodiment illustrated. This seam comprises a body-fabric a supporting four spaced rows of single chain-stitches b . Looped back and forth, in closed-loop or 15 "figure 8" formation, between each outer row of stitches and an adjacent intermediate row, are the embroidery threads c which are presented to the needles by the rearwardly disposed looper-tubes 60. The two intermediate 20 rows of stitches are connected by an embroidery thread d which is looped back and forth in open-loop formation by the forwardly disposed looper-tube 102.

The invention, however, is not to be understood as limited to a four-needle machine as the number of needles used is obviously immaterial. It is also evident that the number of looper-tubes carried by either of the loopers is immaterial and may be varied at will 30 to produce ornamental seams differing in configuration. The present machine may therefore be put to a variety of uses including all of those suggested in my said copending application. The various structural features shown and described are also susceptible of material modification, both in the form and arrangement of the various parts, within the scope of the invention as defined in the appended claims.

Having thus set forth the nature of the invention, what I claim herein is:—

1. In an ornamental stitch sewing machine, in combination, a reciprocating needle and complementary loop-taking means, a 45 looper for the ornamental thread mounted for universal movement transversely of the needle, and actuating connections for said looper including a pivoted toggle-device adapted to project the looper toward the 50 needle, the pivots of said toggle-device being constructed and arranged to move across alinement during the first part of the down-stroke of the needle, whereby the looper is caused to dwell substantially until the needle 55 enters the work.

2. In an ornamental stitch sewing machine, in combination, a reciprocating needle and complementary loop-taking means, a needle-actuating rock-shaft, a crank-pin carried thereby, a looper for the ornamental thread mounted for universal movement transversely of the needle, actuating connections for said looper including a link connected at one end to said crank-pin and

adapted to move into alinement with the 65 centers of said crank-pin and rock-shaft during the first part of the down-stroke of the needle, whereby said looper is caused to dwell substantially until the needle enters the work. 70

3. In a sewing machine, in combination, a lower rotating main-shaft, an upper oscillating needle-shaft, stitch-forming mechanism including a reciprocating needle and complementary loop-taking means actuated by 75 said shafts, a looper for the ornamental thread mounted for movements in mutually transverse directions, a speed-reducing connection between said main-shaft and said looper whereby the latter is vibrated in one 80 direction at half the frequency of the needle reciprocations, and connections between said oscillating needle-shaft and said looper, whereby the latter is vibrated in the other direction in unison with the needle reciprocations. 85

4. In a sewing machine, in combination, feeding mechanism comprising a feed-dog and a presser-foot having a bifurcated shank, and stitch-forming mechanism comprising 90 a reciprocating needle and a co-operating thread-looping implement sustained in rear of said presser-foot and projecting forwardly between the bifurcations of said presser-foot shank. 95

5. In an ornamental stitch sewing machine, in combination, stitch-forming mechanism including a reciprocating needle and complementary loop-taking means, feeding mechanism including a feed-dog and presser-foot having a bifurcated shank, and a looper for the ornamental thread, said looper being supported in rear of the presser-foot and projecting forwardly toward the needle between the bifurcations of said presser-foot 100 shank. 105

6. In a sewing machine, in combination, stitch-forming mechanism including a reciprocating needle, a presser-foot including laterally spaced shank-portions disposed 110 mainly in rear of the needle, and a thread-looping element sustained in rear of the presser-foot and including a forwardly projecting thread-engaging arm disposed between the shank-portions of said presser-foot. 115

7. A sewing machine comprising, in combination, stitch-forming mechanism including a reciprocating needle, feeding mechanism, a presser-bar, a thread-finger support 120 fixed to the presser-bar, a rearwardly directed arm pivoted to said support, an upwardly extending shaft journaled in said arm, a forwardly extending thread-finger carried by said shaft and presenting an ornamental thread to said needle, means for 125 rocking said shaft axially to move the thread-finger laterally of the line of feed,

and means for tilting said shaft to move the thread-finger lengthwise of the line of feed.

8. In a sewing machine, in combination, 5 a reciprocating needle, a loop-taker, a needle-actuating shaft, a loop-taker actuating shaft, a thread-looping implement including a thread-engaging portion sustained for components of motions in mutually 10 transverse directions laterally of the needle, operative connections between said implement and needle-actuating shaft for imparting to said implement one component of its motion and operative connections between 15 said implement and the looper-actuating shaft for imparting to said implement the other component of its motion.
9. In a sewing machine, in combination, 20 a reciprocating needle, a loop-taker, a thread-looping implement for the ornamental thread mounted for vibratory components of motion of different frequencies in transverse directions laterally of said needle, and actuating connections for imparting to said 25 implement said components of motion, said connections including a toggle for producing a substantial dwell in the motion of said implement while in loop-presenting position adjacent the needle-path.
10. In an ornamental stitch sewing machine, in combination, a frame comprising a bracket-arm terminating in a head, stitch- 30

forming mechanism incorporated in said frame and comprising a reciprocating needle and complementary loop-taking means, feeding mechanism, a spring-pressed presser-bar journaled in said head and carrying a presser-foot at its lower extremity, a looper-supporting frame secured to said presser-bar at a point below said head, a looper for the ornamental thread mounted on said frame 40 for universal movement laterally of the needle, and means for driving said looper in a figure 8 path in timed relation with the reciprocations of said needle. 45

11. In an ornamental stitch sewing machine, in combination, a frame comprising a bracket-arm terminating in a head, stitch forming mechanism incorporated in said frame and comprising a reciprocating needle 50 and complementary loop-taking means, feeding mechanism, a spring-pressed presser-bar journaled in said head and carrying a presser-foot at its lower extremity, a looper-supporting frame secured to said presser-bar at a point below said head, loopers for the ornamental threads sustained by said frame for universal movement transversely of said needle, and means for actuating said loopers whereby they are caused to present their respective threads to said needle in alternation. 55

In testimony whereof, I have signed my name to this specification.

ALBERT H. DE VOE.
